UNITED STATES PATENT OFFICE.

BURTON D. MYERS, OF WALLINGFORD, CONNECTICUT, ASSIGNOR TO SIMEON L. AND
GEORGE H. ROGERS CO., OF WALLINGFORD, CONNECTICUT, A CORPORATION.

DESIGN FOR A SPOON, FORK, OR SIMILAR ARTICLE.

44,070.

Specification for Design.

Patented May 20, 1913.

Application filed February 26, 1913. Serial No. 750,883. Term of patent 7 years.

To all whom it may concern:

Be it known that I, BURTON D. MYERS, a citizen of the United States, residing at Wallingford, in the county of New Haven and State of Connecticut, have invented a new, original, and ornamental Design for a Spoon, Fork, or Similar Article; and I do hereby declare the accompanying drawings to be a full, clear, and exact illustration of the same, and which said drawings constitute part of this application, and represent, in—

Figure 1 a face view of a spoon, fork or similar article embodying my design. Fig. 2 a detail perspective view of the same.

I claim:

The ornamental design for a spoon, fork or similar article, as shown.

BURTON D. MYERS.

Witnesses:

JOHN A. MARTIN,
CLIFTON D. MILLER.
